COKING RETORT OVEN

Filed May 23, 1925

UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed May 23, 1925. Serial No. 32,409.

This invention comprehends improvements of general utility in the coking retort oven art; and also comprehends certain improvements especially applicable to coking retort ovens of the well-known cross regenerative type exemplified in the patent to H. Koppers, No. 818,033, dated April 17, 1903, and in the patent to Joseph Becker, No. 1,374,546, dated April 12, 1921.

The invention has for objects the provision of a coking retort oven having, as an important characteristic, a novel system in control of the flow through the flame flues of the heating walls, which permits a considerable reduction not only in the length but in the cross-sectional dimensions or area of the horizontal or bus flue located at the top of the vertical flame flues, which is substantially alongside the top level of the coal charge in the adjacent coking chambers and connecting a plurality of the vertical flame flues with each other, while permitting the employment of the usual system of flow through the flues, wherein upflow in the flues on one side of the battery takes place concurrently with downflow in the flues on the opposite side. The present invention permits, for example, the substitution of a pair of horizontal flues of relatively smaller but constant cross-sectional area in each heating wall for the usual single horizontal flue and each horizontal flue is subdivided into a plurality of short horizontal flues that serve a restricted number, in the present embodiment, five, vertical flame flues. Consequently the cross-sectional area of the horizontal flues may be greatly reduced as each is required to accommodate the flow for a comparatively few, in the present instance, five, vertical flame flues. The above-stated reduction in size of the horizontal flues is an important advantage for the reason that it enables a considerable thickening and strengthening of the walls of the oven structure in the region of the horizontal flues. It permits the upward extension of the flame flues for extension of the flame heating, thereby permitting more rapid coking of the charge by direct flame heating up to substantially the top of the coal charge in the adjoining oven, and provides, by reason of the

reduction in the cross-sectional area of the horizontal flue and the maintaining of the cross-sectional area constant throughout its length, for the provision of vertically elongated brickwork that constitutes an insulation alongside the crown space in the contiguous coking chamber, which brickwork prevents destructive decomposition, of the gaseous products of distillation that accumulate in the crown space of the coking chamber, that might otherwise occur by reason of the extension of the vertical flame flues and the resulting extension of direct flame heating in the vertical flame flues.

In addition to the objects recited above, the invention contemplates a novel regenerator construction and system of flow therethrough and through the flues, promoting uniformity of distribution, and has for other objects such other improvements or advantages in construction and operation as are found to obtain in the structures and devices hereinafter described or claimed.

In the accompanying drawings, forming a part of this specification, and showing, for purposes of exemplification, a preferred form and manner in which the invention may be embodied and practiced, but without limiting the claimed invention to such illustrative instance or instances:

Figure 1 is a crosswise vertical section taken through a coke oven battery embodying features above specified and equipped with the improvements of the present invention, the view being taken longitudinally through a heating wall constituted of vertical combustion flues and through a pair of regenerators, in planes indicated by the line C—C of Fig. 2.

Fig. 2 is a composite vertical sectional elevational view taken longitudinally of a coke oven battery in planes indicated by the lines A—A and B—B of Fig. 1.

Fig. 3 is a horizontal sectional elevational view taken in the plane indicated by the line D—D of Fig. 1.

The same characters of reference indicate the same parts throughout the several views of the drawings.

In the embodiment illustrated in the draw-

ings, the invention is incorporated in a combination coke oven battery, i. e., a battery having provision for being operated either with producer gas for fuel or with coke oven gas burned in an atmosphere of ordinary pre-heated air, such as is utilized in ordinary coke ovens or with coke oven gas burned in an atmosphere containing both air and a neutral gaseous diluent which is introduced into the flame flues separately from the air. A combination coke oven battery having these features is described and claimed in the patent of Joseph Becker for a coking retort oven Patent No. 1,416,322.

For convenience, the present description will be confined to the present illustrative embodiment of the invention in such a combination oven battery; the novel features and improvements made by the invention are susceptible of other applications, such, for example, as ordinary so-called "coke ovens" employing coke oven gas as a fuel, or ordinary so-called "gas ovens" employing producer gas as a fuel; hence, the scope of the invention is not confined to the specific use and specific embodiment herein described as an illustrative example.

Referring to the drawings: There are illustrated views of a coke oven battery or plant of the by-product type having features above specified. Said oven battery embodies in its construction a plurality of crosswise elongated heating walls, 11, 11 and a plurality of intermediate crosswise elongated vertical coking chambers 12. The heating walls 11 form the side walls of the respective coking chambers 12, as shown more particularly in Fig. 2, and, in the present instance, are supported by the heavy supporting or pillar walls 13, 13 which extend crosswise of the battery and are located, as shown in Fig. 2, beneath the respective heating walls 11, 11. These pillar walls collectively form the main support for the entire super-structure of the oven battery and are themselves supported upon a flat mat or platform which constitutes the sub-foundation on which the entire battery rests.

The coal to be coked is charged into the several coking chambers or ovens through charging holes 14 located in the top 15 of the oven battery and positioned directly above the oven or chambers 12, as shown in Figs. 2 and 3. These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets and thence through ascension pipes (not shown) into the usual gas collecting main which carries the distilla-

tion products to the by-product recovery apparatus.

Heat for coking the charges of coal in the several ovens or chambers 12 is derived from the heating walls 11, which, as above mentioned, extend crosswise of the battery at the sides of the coking chambers. Referring now more particularly to Figs. 1 and 2, each heating wall 11 is constituted of a plurality of flame or combustion flues 17. The flame flues of each heating wall are, in accordance with the present embodiment of the invention, operatively disposed into two groups, a pusher side group F and a coke side group G. When the flame flues on one side of the battery, for example the pusher side are burning, that is to say, operating for upflow, the flame flues of the coke side group of the same heating wall are operating for downflow to permit exhaust of the waste gases. Reversal of the battery is effected to cause the coke side group of heating flues to operate as upflow or burning flues and the pusher side group as downflow flues.

The crosswise regenerators 18 of the regenerator oven or battery are located in planes beneath the planes of the aforesaid heating walls 11 and coking chambers 12, and, in the present instance, extend in parallelism beneath the coking chambers and between the pillar walls 13. Located in the middle lengthwise vertical plane of the coke oven battery, is a vertical partition 19, as shown in Fig. 1, which partition extends all the way up from the mat of the battery to the bottom of the overlying coking chamber and from one to the other of the pillar walls 13. The regenerators, which are respectively located on opposite sides of the battery extend inwardly to said partition 19 and are separated thereby as clearly shown in Fig. 1. This arrangement provides pairs of regenerators extending crosswise of the battery, each pair being constituted of a pusher side regenerator, indicated by the reference character F' and a coke side regenerator indicated by the reference character G'. The pusher side regenerators F' correspond to the pusher side groups of flues F and the coke side regenerators G' correspond to the coke side groups of flues G.

Each regenerator 18 is a chamber containing open brick work, commonly called checker-work, and indicated at 20, with distributing sole channels 21 underneath such checker-work, the channels forming the soles of such chambers and opening up into the checker-work. If desired, each regenerator 18 may be divided, as shown in the present embodiment of the invention, by a vertical partition 22 which extends longitudinally of the regenerator and serves to separate the regenerator into two flow compartments located respectively on the opposite sides of such partition 22.

The several regenerators are heated, in al-

ternation by the hot combustion products that are exhausted from the flame or combustion flues hereinbefore mentioned and then impart such heat to the medium that they feed into these flame flues. Each regenerator 18 communicates with the corresponding groups of flues 17 of the two heating walls adjacent to and respectively located on the opposite sides of the regenerator, by means of ducts 23, each duct leading upwardly from a regenerator into a flue, as shown in Fig. 2. Thus, each regenerator of the group F' is connected with all of the flues of the two adjacently disposed groups F; and similarly each regenerator of the group G' is connected with all of the flues of the two adjacently disposed groups G. With this construction and arrangement, every group of flues F or G is connected by ducts 23 with two adjacently disposed regenerators of the corresponding group, and, consequently, each group of flues may be fed with gaseous medium from two separate regenerators. The advantage of this arrangement will be clear in the hereinafter described operation of the battery.

In the present embodiment of the invention, the groups of flues on one side of the battery are operating for flow in one direction, while concurrently the groups of flues on the other side of the battery are operating for flow in the opposite direction, and consequently there is maintained flow in reverse directions through the regenerators that are respectively positioned on opposite sides of the central longitudinal partition 19. The reversal in flow through the flame flues 17 and their communicably connected regenerators may thus be said to take place crosswise of the battery, in accordance with the common practice in this art. The reversal of the battery is effected at the end of an operating period determined by practice, and by means of any preferred type of reversing mechanism. The function of such reversal is as follows: The regenerators that prior to the reversal operated as inflow regenerators become outflow regenerators, and the outflow operating regenerators become inflow operating regenerators; the upburning series of flues switches functions with the downburning series of flues on the opposite side of battery and the supply of gas is turned off from the previously upburning flues and turned on into the mains of the previously downburning flues.

Each flame flue 17 of each heating wall has in its top a port or opening 24 for draft and the passage of combustion products or waste gas from the flame within the flue. These ports 24 open up into horizontal or bus flues 25 formed in the heating walls and connecting all of the vertical flues that communicate with such horizontal flues 25 by means of the ports 24. According to the invention there are in each heating wall a plurality of, in

the present instance, two of such horizontal flues 25 positioned end to end with respect to each other and respectively located on opposite sides of the central dividing line L. By reason of the fact that there is a plurality of such horizontal flues 25 in each heating wall, these flues 25 are not required to be of so great capacity as that necessary in present practice and consequently the cross sectional area of each horizontal flue 25 may be materially reduced proportionately with the length of such flue, with the result that the thickness and strength of the heating walls are substantially increased in the region of the horizontal flues. Moreover, because of the fact that each horizontal flue 25 communicates with a substantially reduced number of vertical flues, in the present instance, half of the flues of the heating wall, uniformity and distribution of the flow through the vertical flues and the communicating regenerators is greatly promoted.

As shown, each horizontal flue 25 is of relatively reduced but constant cross-sectional area and the two horizontal flues are communicably connected with each other by means of passageways or connection flues 26 which extend crosswise of the battery substantially throughout the length of the flues 25 and which are also of constant but of relatively greater cross-sectional area than the horizontal flues 25. The connection flues 26 are located at a higher level than the oven chambers and so may be and are of large cross-sectional areas that insure low velocities and equalized distribution of flow. The flues 25 and passageways or connection flues 26 are communicably connected with each other by means of a plurality of elongated vertical ducts 26' so that, as shown in the present instance, the horizontal flues 25 and each of the vertical ducts 26' need only be large enough to take care of the flow from five vertical flues instead of from all of the flues on one side of the central partition L and so the flow may be at very low velocity. As the flow of gases through the flues is under equalized pressure and low velocity, the gases from each of the flues will tend to flow through the nearest outlet or duct 26', for instance each duct 26' will operate for flow from two and one-half flues on each side of it.

Thus the flow from a pusher side group F of flues may pass into the horizontal flue 25 thence through the plurality of ducts 26' into the connecting flue 26 then through the plurality of vertical ducts 26' to the horizontal flue 25 of the coke side group G of the same heating wall into the vertical flues therein. On reversal the flow from the coke side group G of each heating wall passes over through the horizontal flue 25, ducts 26' and connecting channel or flue 26 into the pusher side group of the same heating wall.

The provision of a plurality of vertical

ducts 26' enables the reduction in cross-sectional dimensions and vertical extension of the horizontal flues 25 and connecting flues 26 and also permits of their being of constant cross-sectional area which affords ample space for flow of the gases and also permits of a row of vertical elongated brickwork 27' arranged in the same vertical plane as is the crown space H in the adjoining coking chamber, thereby providing heat insulation along-side the crown space H of the coking chamber wherein the valuable by-product gases evolved in the distillation operation accumulate and flow through to the usual distillate gas offtake. Such insulation brickwork is not only advantageous structurally but is also desirable in prevention of overheating and decomposing of the valuable gases of distillation accumulating in the crown spaces in the adjoining coking chamber. The minimum height of the crown-space H may vary with different ovens dependent upon the kind and quality of coal they are designed to coke and the contemplated size and shape of the chamber therefor and is determined in practice in the following manner well known in the art. The size of the usual initial space required to be left along the top of the oven for off-flow of gas from a charge while being coked is governed by the principal coal intended to be employed in the oven chamber, and is computed from the known gas yield of a definite quantity of a given coal under the shortest coking time contemplated. This computed size determines the top level to which the chamber may be charged with raw coal, which level is then mechanically fixed by locating the lower level of the usual coal-leveler door on the pusher side of the chamber at such computed top level for the coal charge. The final level of the crown-space H is then ascertained from such top level by scientifically computing from the known shrinking characteristics of the coal the top level to which the given raw coal charge will shrink at the end of the coking period. The horizontal flow-duct means 25 are then, for instance, located in their respective heating walls so that their tops will be substantially up to the computed top level for finished coked charges, as exemplified in Fig. 2. In this manner, the minimum height of the crown-space H and the top level for coked charges are mechanically fixed and from such horizontal flues 25 the vertical combustion flues 17, ducts 26' and upper horizontal flow-duct means, or further collecting or connecting flue 26, are located relative to the coking chamber, in the manner shown on the drawings, so that the heating of the coking chamber is maintained upwardly to nearly the top level for finished coke charges in the chambers, overheating of the gas in the crown-space H avoided, and a relatively thin cool top assured at the top of the coke charge by

means of the location and dimensions of the horizontal flue 25. For example, in an oven having the mean dimensions A, 16.5 inches; B, 14 feet; oven length inside doors, 42 feet, 6 inches; and designed for coking in 16.83 hours 19.13 tons of coal averaging 759 cubic feet and 50.4 pounds per cubic foot in the chamber: the determined top level E for raw coal charges was 12 inches, the top level C for the horizontal flue and the substantially corresponding final level for the crown-space H and top level for the finished coke was 28 inches, and the depth D of the horizontal flue was 5.5 inches. In another oven having the mean dimensions A, 14 inches; B, 13 feet; oven length inside doors 40 feet, 8 inches; and designed for coking in 18 hours 12.8 tons of coal averaging 545 cubic feet and 47 pounds per cubic foot in the chamber; the determined top level E for raw coal charges was 18 inches, the top level C for the horizontal flue and the substantially corresponding final level for the crown-space H and top level for the finished coke was 30 inches, and the depth D of the horizontal flue was 5.5 inches. And for an oven to be principally employed for coal of still less shrinking type, the difference between E and C would of course be still less. The employment of vertical partitions 28' in the horizontal flues 25, one each for every five vertical flame flues, i. e., one intermediate each two vertical ducts 26' not only improves the oven structurally but also serves to restrict the flow to and from each group of five vertical flues through the ducts 26' thereby greatly facilitating the distribution and flow to and from the vertical flame flues. While it is desirable to utilize the vertical partitions 28' it is entirely practical to omit them as the flow to and from the flues is so regulated as to be equalized in accordance with their respective temperature and pressure differentials. Consequently the flow to and from each two and one-half flues on each side of each vertical duct 26' will be towards the nearest central duct 26'.

The draft through the ports 24 may be regulated by means of the usual movable dampers or sliding bricks 27, positioned in the usual manner over the top of the vertical ducts 26' and adapted to be reached by access flues 28 which extend from the top of the horizontal flues 25 in each heating wall to the top 15 of the battery, there being an access flue positioned over each flame or combustion flue of each heating wall. As shown in Fig. 1, the upper portion of the vertically elongated brickwork 27' is also constituted of access flues 27A which are in line with the access flues 28 in the top 15 immediately above. These access flues 27A may be closed by covers 28A adapted to seat over the top of such access flues.

But by reason of the fact that the collecting flue 26 may be of such large cross-area

and that each section of the horizontal flues 25, which ports through its duct 26' into the collecting flue 26, is required to accommodate the volume of waste-gas from or to only a very limited number of vertical flues, the flow velocities are so low that the distribution from and to the vertical flues may be made uniform without any employment or setting of the sliding bricks, such as 27, in the flue 26 or in the flues 25.

Extending crosswise of the battery in each pillar wall 13 and located beneath the heating wall 11 thereabove, is a pair of gas supply channels 29. These channels 29 are for the purpose of supplying coke oven gas to the several flame flues on each side of the central line L and, for this purpose, the channel 29, communicates with the individual flues of the pusher side group F by means of ducts 31 that lead from such channel 29 individually into the bottoms of individual flues; and the channel 29 which supplies the several flues of the coke side group G communicates therewith by means of similar connecting ducts. Within the several ducts are disposed the usual nozzles 32. The supply of coke oven gas to the respective channels 29 is derived from coke oven gas mains of the usual type and respectively located on the opposite sides of the battery and extending longitudinally therewith. Suitable means is provided for admitting or shutting off the supply of gas with respect to each pair of channels 29, it being understood that the supply of gas is maintained in one of the channels of each pair while shut off from the other.

For operating the battery alternatively with the use of a special generator gas, such as producer gas as a fuel, alternately disposed inflow operating regenerators may be optionally connected with a producer gas main, by mechanism such as is disclosed in the before mentioned Patent, No. 1,416,322, whereas the regenerators that are intermediate such alternately disposed regenerators are supplied with air, so that producer gas and air may be conveyed into the upburning flame flues.

The operation of the battery, when using a special generator gas, such as ordinary producer gas as a fuel, is as follows: the supply of coke oven gas to the coke oven gas main and to all of the coke oven gas channels 29 is cut off. A supply of producer gas is permitted to flow into the alternate regenerators, such as are operating for inflow, and a supply of air enters the intermediately disposed regenerators. As each flame flue is communicably connected with two regenerators, and each regenerator with the flame flues of two adjacently disposed heating walls, gas and air preheated in the respective gas and air regenerators enter and burn upwardly in each inflow operating vertical flue. The waste gases from the upburning flues pass into the

horizontal flues 25, ducts 26' and thence through the channel 26 to the horizontal flues on the opposite side of the battery. From the last mentioned horizontal flues, the exhaust gases pass downwardly through their communicably connected flame flues and finally through all of the regenerators on the downflow side of the battery to the waste gas tunnel, through which the waste gases are conveyed to the stack. On reversal of the flow, the inflow operating regenerators and their communicably connected flame or combustion flues become outflow regenerators and concurrently the outflow operating regenerators and flues become inflow operating regenerators and flues.

In operating the oven with coke oven gas in the ordinary manner, the supply of producer gas to alternate regenerators is shut off and air is permitted to flow into all of the inflow operating regenerators. During coke oven gas operation, the supply of coke oven gas in the channels 29 is fed into the upburning flues. The reversing mechanism is operated at each reversal to place all of the inflow operating regenerators in communication with the outer air and concurrently all of the outflow operating regenerators in communication with the exhaust.

A further mode of operation is with coke oven gas as a fuel, combined with a supply of neutral gaseous diluent to the upburning flues. In so operating the batteries the supply of producer gas is turned off and the supply of coke oven gas is turned on. Instead however of permitting air to flow into alternate regenerators that are intermediate such alternate regenerators, waste gas is permitted to flow into alternate inflow operating regenerators and is delivered thereby to the upburning flame flues. The admission into each of the upburning flues of a supply of neutral gaseous diluent, such as waste gas, along with the air, is effective to lengthen greatly the flames within such flues and to prevent the localization of the hottest flame temperature in the extreme lower portions of the flues.

The invention as hereinabove set forth is embodied in a particular form of construction but may be variously embodied within the scope of the claims hereinafter made.

I claim:

1. In a coking retort oven, in combination: a plurality of parallel coking chambers; heating walls between and contiguous thereto and each comprising individual vertical flame flues disposed in groups operable alternately for upflow combustion and downflow of combustion products; a horizontal flue of relatively small but constant cross-sectional area, immediately above each of said groups and directly communicating with the vertical flues within the group; a connection flue for each of the heating walls, above the

horizontal flues of the heating wall, the connection-flue being of relatively large cross-sectional area, and communicably connecting, by duct means the aforesaid horizontal flues of one group with the horizontal flues of another group of vertical flues of the same heating wall; a plurality of partitions separating each of said horizontal flues, and said duct means comprising a vertical duct 10 midway each two consecutive partitions communicably connecting the flues between each two consecutive partitions with the connection-flue.

2. In a coking retort oven, in combination: a plurality of parallel coking chambers; 15 heating-walls between and contiguous thereto and each comprising individual vertical flame flues disposed in groups operable alternately for upflow combustion and downflow 20 of combustion products; a horizontal flue of constant cross-sectional area immediately above each of said groups and directly communicating with the vertical flues within the group; a connection-flue for each of the heating walls, above the horizontal flues of the heating wall, the connection-flue being of constant cross-sectional area and communicably connecting, by duct means the aforesaid horizontal flues of one group with the 25 horizontal flues of another group of vertical flues of the same heating wall; said horizontal flues being separated by partitions; and said duct means comprising ducts individual to each of the horizontal flues, communicably 30 connecting them with the connection-flue.

3. In a coking retort oven, in combination: a series of alternate horizontal coking chambers and heating walls therefor arranged side-by-side in a row, each of said coking 40 chambers having a crown-space having thickened lateral walls at the upper part of the coking chamber and being adapted for being charged full of coal save for a gas space in the crown-space thereof left for collecting gas above the coal charges therein and each of said heating walls comprising 45 vertical flame-flues disposed in two groups for upflow and downflow in alternation with each other and extending substantially up to nearly, but below, the top level to which the 50 adjoining chambers are adapted for being charged with coal, to effect uniformity of coking of said charges, horizontal flues immediately above the two groups of vertical 55 flues and communicating with the upper parts of the vertical flues in said two groups, said horizontal flues being of small cross-sectional area and so restricted in vertical extension that they are located below the 60 level for which the adjoining coking chambers are adapted for being charged and yet allow the vertical flame-flues to extend upwardly to nearly the top level for coked charges; a connection-flue of relatively large 65 cross-sectional area, for each of the heating

walls, and disposed lengthwise thereof at a higher level than the gas collecting crown-space of the adjoining coking chambers and communicably connected by a plurality of upwardly directed flow ducts with the horizontal flues that respectively serve the upflow and downflow vertical flues in such heating wall; the said upwardly directed flow ducts being horizontally spaced along the horizontal length of the heating wall so that there is provided a plurality of said ducts for each of the two groups of vertical flues in the heating wall and so that each of said ducts is adapted to accommodate gas flow for a different plurality of the vertical flues 70 within its group.

4. In a coking retort oven, in combination: a series of alternate horizontal cooking chambers and heating walls therefor, arranged side-by-side in a row, each of said heating 80 walls comprising vertical combustion flues disposed in two groups and each of said coking chambers extending above the levels of the tops of the combustion flues in the heating walls contiguous thereto; lower horizontal flow-duct means immediately above each of said groups and communicating with the vertical flues within the group; upper horizontal flow-duct means for each of the heating walls disposed above the lower horizontal flow-duct 85 means of the heating wall and communicably connecting, through distributed ducts, the lower horizontal flow-duct means for one group with the lower horizontal flow-duct means for the other group of vertical flues 90 in the heating wall; each of said upper horizontal flow-duct means being located above the levels of the tops of the coking chambers and each of said lower horizontal flow-duct means being located entirely below said levels 95 and so disposed as to be entirely at a spaced distance below the levels of the tops of said chambers, and the said distributed ducts for each of the heating walls being located between the upper and the lower horizontal flow-duct means of the heating wall and being distributed in horizontally spaced relationship therealong so that there is provided a plurality of said ducts for each of the two groups of vertical flues in the heating wall 100 and so that each of said ducts is adapted to accommodate gas flow for a plurality of the vertical flues of the group thereof that they respectively serve; and crosswise regenerators communicably connected directly with 105 said vertical combustion flues.

5. In a coking retort oven, in combination: a series of alternate horizontal coking chambers and heating walls therefor, arranged side-by-side in a row, each of said 110 heating walls comprising vertical combustion flues disposed in two groups and each of said coking chambers extending above the levels of the tops of the combustion flues in the heating walls contiguous thereto; lower horizon- 115

tal flow-duct means immediately above each of said groups and communicating with the vertical flues within the group; upper horizontal flow-duct means for each of the heating walls disposed above the lower horizontal flow-duct means of the heating wall and communicably connecting, through distributed ducts, the lower horizontal flow-duct means for one group with the lower horizontal flow-duct means for the other group of vertical flues in the heating wall; each of said upper horizontal flow-duct means being located above the levels of the tops of the coking chambers and each of said lower horizontal flow-duct means being located entirely below said levels and so disposed as to be entirely at a spaced distance below the levels of the tops of said chambers, and the said distributed ducts for each of the heating walls being located between the upper and the lower horizontal flow-duct means of the heating wall and being distributed in horizontally spaced relationship therealong so that there is provided a plurality of said ducts for each of two groups of vertical flues in the heating wall and so that each of said ducts is adapted to accommodate gas flow for a plurality of the vertical flues of the group thereof that they respectively serve; and regenerators communicably connected with said vertical combustion flues.

6. In a coking retort oven, in combination: a series of alternate horizontal coking chambers and heating walls therefor, arranged side-by-side in a row, each of said heating walls comprising vertical combustion flues disposed in two groups and each of said coking chambers extending above the levels of the tops of the combustion flues in the heating walls contiguous thereto; lower horizontal flow-duct means immediately above each of said groups and communicating with the vertical flues within the group; upper horizontal flow-duct means for each of the heating walls disposed above the lower horizontal flow-duct means of the heating wall and communicably connecting, through distributed ducts, the lower horizontal flow-duct means for one group with the lower horizontal flow-duct means for the other group of vertical flues in the heating wall; each of said upper horizontal flow-duct means being located above the levels of the tops of the coking chambers and each of said lower horizontal flow-duct means being located entirely below said levels and so disposed as to be entirely at a spaced distance below the levels of the tops of said chambers, and the said distributed ducts for each of the heating walls being located between the upper and the lower horizontal flow-duct means of the heating wall and being distributed in horizontally spaced relationship therealong so that there is provided a plurality of said ducts for each of the two groups of vertical flues in the heating wall and so that each of said ducts is adapted to accommodate gas flow for a plurality of the vertical flues of the group thereof that they respectively serve.

flues in the heating wall and so that each of said ducts is adapted to accommodate gas flow for a plurality of the vertical flues of the group thereof that they respectively serve.

7. In a coking retort oven, in combination: 70 a series of alternate side-by-side horizontal coking chambers and intermediate heating-walls therefor, said heating-walls comprising vertical flame-flues whose tops port directly into horizontal collecting flues that are so restricted in height that they are located below the level to which the adjoining coking-chambers are adapted for being charged and yet allow the flame-flues to extend upwardly to nearly the top level for coked charges; a 80 further collecting-flue extending lengthwise over each heating-wall and located above the level of the top of the adjoining coking chambers; a multiplicity of vertical ducts connecting said further collecting-flue at several 85 points along each half of its length with the aforesaid horizontal collecting-flues, said ducts being spaced at such intervals that each may serve to convey combustion-products from and to substantially not more than half 90 the number of vertical flame-flues that may concurrently serve for up-flow combustion or for down-flow off-take of combustion products; and regenerators communicating with 95 said flame-flues.

8. In a coking retort oven battery, in combination: a series of alternate horizontal coking chambers and heating walls therefor arranged side-by-side in a row, each of said heating walls comprising vertical flame-flues 100 arranged in a row disposed in groups operable in alternation with each other for up-flow combustion and downflow of combustion products; regenerators communicating with said flame-flues; horizontal flow-duct means immediately above and directly communicating with the vertical flame-flues of each of the aforesaid groups in each heating wall and respectively disposed at a spaced distance below the tops of the adjacent coking chambers; 105 a connection flue above the horizontal flow-duct means in each heating wall and disposed higher than the tops of said coking chamber, for passing combustion products from a horizontal flow-duct means of one group to a horizontal flow-duct means of a reverse flow group of vertical flues in the same heating wall; and a plurality of upwardly directed flow ducts directly connecting each of the 110 horizontal-flow duct means in each heating wall with the aforesaid connection flue therefor; the said flow ducts of each of said horizontal-flow duct means being distributed therealong so that each of these accommodates gas flow to and from a plurality of vertical flues between each two of them; whereby each of said horizontal-flow duct means may be restricted in height and cross-sectional area so as to accommodate only the flow of 115 combustion products to and from substan- 120

tially not more than half the number of vertical flame-flues that may concurrently serve for upflow combustion or for down-flow off-take of combustion products.

- 5 9. In a coking retort oven, in combination: a plurality of parallel coking chambers; heating-walls between and contiguous thereto and each comprising individual vertical flame flues disposed in groups operable alternately
10 for upflow combustion and downflow of combustion products; a horizontal flue immediately above each of said groups and directly communicating with the vertical flues within the group; a connection-flue, for each of the
15 heating walls, above the horizontal flues of the heating wall, the connection-flue communicably connecting, by duct means, the aforesaid horizontal flues of one group with the horizontal flues of another group of vertical
20 flues of the same heating-wall; a plurality of partitions separating each of said horizontal flues, and said duct means comprising a vertical duct midway each two consecutive partitions communicably connecting the flues between each two consecutive partitions with the connection flue.

- 10 10. In a coking retort oven, in combination: a plurality of parallel coking chambers; heating-walls between and contiguous thereto
20 and each comprising individual vertical flame flues disposed in groups operable alternately for upflow combustion and downflow of combustion products; a horizontal flue immediately above each of said groups and directly
30 communicating with the vertical flues within the group; a connection-flue, for each of the heating walls, above the horizontal flues of the heating-wall, the connection-flue communicably connecting, by duct means, the aforesaid horizontal flues of one group with the horizontal flues of another group of vertical
35 flues of the same heating-wall; said horizontal flues being separated by partitions, and said duct means comprising ducts individual
40 to each of the horizontal flues, communicably connecting them with the connection-flue.

In testimony whereof I have hereunto set my hand.

JOSEPH VAN ACKEREN.
